UNITED STATES PATENT OFFICE.

JOHN C. DODS, OF ST. LOUIS, MISSOURI, ASSIGNOR TO JAMES GREEN, OF SAME PLACE.

FURNACE FOR THE MANUFACTURE OF GAS.

SPECIFICATION forming part of Letters Patent No. 501,457, dated July 11, 1893.

Application filed February 20, 1893. Serial No. 463,052. (No model.)

To all whom it may concern:

Be it known that I, JOHN C. DODS, of the city of St. Louis, in the State of Missouri, have invented a certain new and useful Improvement 5 in Furnaces for the Manufacture of Gas, of which the following is a full, clear, and exact description, reference being had to the accompanying drawings, forming part of this specification.

10 My invention relates to certain improvements in furnaces for the manufacture of gas, and my invention consists in novel features of construction hereinafter fully described and pointed out in the claims.

15 Figure I is a front elevation of my improved furnace. Fig. II is a vertical section, taken on line II—II, Fig. I. Fig. III is a vertical section, taken on the irregular line III—III, Fig. IV. Fig. IV is a vertical, transverse section, taken on line IV—IV, Fig. II. Fig. V is a horizontal section, the portion from A to B being taken on line A—B, Fig. III; the portion from B to C being taken on line B—C, Fig. III; the portion from C to D being taken 20 on line C—D, Fig. IV; and the portion from D to E being taken on line D—E, Fig. IV.

25 Referring to the drawings, 1 represents the front of the furnace.

30 2 are the side walls, 3 the rear wall, 4 the chimneys or up-takes, 5 the fire-box, and 6 the retorts. These parts may be of any desired form or construction.

35 I have shown a double furnace, or two furnaces side by side, but a single furnace or more than two furnaces may be used, and embody my invention.

40 The air to supply combustion, and form carbonic oxide, enters the lower, horizontal flues 7, passing to the rear of the furnace and re-

45 turning to the front again enters the fire-box, as indicated by the arrows in the lower part of Fig. V. These horizontal flues 7 are of approximately triangular shape in cross-section and have their widest portion at the bottom on one side of the down-flue and their narrow- 50 est portion at the top on the other side of the down-flue. The air which enters above the fire-box to complete combustion to form car-

bonic acid gas is admitted through the flues 8, see Fig. I, and passes to the rear of the furnace, and returns to the front of the furnace

again, where it escapes from the flue 8 into a like flue 8 above, through an opening 9, (see Fig. IV.) It passes back to the rear of the furnace through this second flue 8, and forwardly again, when it escapes through an opening 10 into a third flue 8, and passes through a passage 11 into the chamber 12, over the fire-box, where it unites with the products of combustion. The flues 8 are also of approximately triangular shape in cross-section having their widest portion at the bottom on one side of the down-flue and their narrowest portion at the top on the other side of the down-flue, the narrowest portion of one flue meeting the narrowest portion of the flue above and the widest portion at the top meeting the widest portion of the flue above so that a vertical zigzag arrangement of spaces or chambers extends upward between each pair of flues as shown in Fig. IV. The flues 8 as well as the flues 7, are preferably arranged on each side of the fire-box, and between these flues, on each side of the fire-box in the spaces or chambers is a series of flues 13 ar- 65 ranged in zigzag form vertically, while they extend horizontally the length of the furnace. The flames and products of combustion enter the top flue 13, through openings 14, com- 70 municating with the retort chamber, and pass from one flue 13 to the next flue beneath through openings 15, (see Fig. III,) and finally escape into a bottom flue 16 which conducts them to the chimney or uptake 4, as shown in Fig. III.

75 The down flues 13 are accessible through openings in the front wall of the furnace, which are closed by plugs 17, and by removing these plugs, the flues can be readily cleaned out.

80 By arranging the flues 7 and 8 on each side of the flues 13, the air is highly heated before it is admitted to the furnace, and the efficiency of the furnace is thus greatly increased, while the arrangement of the flues 13 afford 95 the best results in utilizing the escaping heat, and their arrangement is such that they can be readily cleaned out, by simply removing the plugs 17.

90 The tiling is constructed throughout of unequal lengths for the purpose of forming broken joints longitudinally of the furnace.

By constructing the tiling of tri-angular shape in cross-section, I provide a very essential feature in a furnace of the class to which this invention relates, for the reason that by constructing the flues in this manner, there is obtained a great economy in space in the size of the furnace, and consequently in the condensed area in which the gas is manufactured and by the arrangement specified the passage of air is always from a larger portion of the flue into a larger portion of the adjoining flue so that the passage of air is as easy as it would be were the diameters of the flues of equal dimensions both above and below, while at the same time the great saving in dimensions of the furnace and its consequent advantages are embodied.

20 represents the door of the fire-box.

21 is the door closing the opening through which the fuel is admitted, and which is preferably placed on or about the floor line 22.

The upper flue 8 is preferably provided with a register 30, (see Figs. I and V,) which is designed to be used when the fire is first started, to admit additional oxygen directly over the fire-box.

I claim as my invention—

1. A recuperative furnace for the manufacture of gas comprising the tiling in the

flues 7, 8, of approximately triangular shape 30 in cross-section; said tiling being alternately inverted so that the larger base of one flue 8 communicates to the larger top of the adjoining flue 8, or vice versa; said tiling being constructed throughout of unequal lengths 35 for the purpose of forming broken joints longitudinally of the furnace; and the vertical zigzag shaped down flues 13 substantially as described.

2. A recuperative furnace for the manufacture of gas comprising a fire-box, the horizontal flue 7, of approximately triangular shape in cross-section, passing to the rear of the furnace and returning to the front again and entering the fire-box, the horizontal flues 45 8, of approximately triangular shape in cross-section, passing to the rear of the furnace and returning to the front again, connected with each other and with the combustion chamber, and the vertical zigzag down-flues 50 13 located between the horizontal flues and extending the length of the furnace; substantially as described.

JOHN C. DODS.

In presence of—

ALBERT M. EBERSOLE,
E. S. KNIGHT.
